ATTORNEY.

UNITED STATES PATENT OFFICE.

DAVID G. GAY, OF PLEASANT HILL, OREGON.

TRACE OR HARNESS BUCKLE.

SPECIFICATION forming part of Letters Patent No. 316,256, dated April 21, 1885.

Application filed January 2, 1884. (No model.)

To all whom it may concern:

Be it known that I, DAVID G. GAY, a citizen of the United States, residing at Pleasant Hill, in the county of Lane and State of Oregon, have invented certain new and useful Improvements in Trace, Hame, and Tug Buckles; and I do declare the following to be a full, clear, and exact description of the invention, such as will enable others skilled in the art 10 to which it appertains to make and use the same, reference being had to the accompanying drawings, and to the letters and figures of reference marked thereon, which form a part of this specification.

15 My invention relates to buckles; and it consists in certain details of construction and arrangement of the several parts, as will be hereinafter more fully set forth in the specification and pointed out in the accompanying 20 drawings, in which—

Figure 1 is a perspective view of my improved buckle having the harness-straps secured in place. Fig. 2 is a longitudinal section of same. Fig. 3 is a plan view of the buckle-plate, and Fig. 4 a side elevation of the locking-tongue.

A buckle of this character is preferably adapted for harness, and in positions where great strain is liable to occur. It may of course be used wherever the ordinary buckle is used.

Referring more particularly to the drawings, in which similar letters of reference refer to similar parts in the several figures, it will be seen that the buckle consists, essentially, of a locking-tongue, A, the holding rings or bands B B', and the plate C.

The tongue-plate A is pivotally secured to band B by a hinge, m, or in any other well-known or suitable way. This allows the tongue-bar to be turned up and its locking end a' freed from the bar B'. This bar A at its free end has a shoulder, a, and an extension, a''. The extension passes under the band 40 B', the shoulder a preventing the band slipping forward. Underneath the extension a'' is a projecting lug, a', which enters a hole in strap D when the buckle is in place. The band B has at the middle of its under side a lug, b, Fig. 2, which enters a hole in strap E. The plate C also has lugs g, similar to the ones 45

just described, which are adapted to enter holes in the strap F.

The bands B and B' are placed in vertical positions and enter the spaces left between the 55 sides and the projections c. This allows them to be moved backward or forward, but prevents any lateral motion, and said projections c serve to prevent the bands from becoming detached from the buckle-frame.

60 The plate C has two lips, c', on its under side which form a support for the strap F when it is in place.

In use the tongue-bar is turned on the band B, so that the strap D can be slipped between 65 the sides of the bands. The strap E having been inserted between the sides of the band and underneath plate C, the lugs g enter the holes in the end of the strap. The lugs g enter holes in strap F, and when the tongue-bar 70 A is put in place, as shown in Fig. 1, the several parts hold the respective straps firmly. The several parts are strong, and the liability to break and get out of order is avoided.

Having thus described my invention, what I 75 claim as new, and desire to secure by Letters Patent, is—

1. In a buckle, the combination, with strap-holding bands and plate having lugs, as described, of a locking-tongue bar pivotally secured to one of the strap-bands, and provided with an engaging-lug, substantially as and for the purpose set forth.

2. In combination with a buckle-frame, the tongue-plate A, having the shouldered extension and the engaging-lug a', as and for the purpose set forth.

3. In combination with a buckle-frame, the strap-bands B and B', one of which is provided with an engaging-lug, b, as and for the 90 purpose set forth.

4. In a buckle, the frame or plate C, having lips c', projections c, and lugs g, in combination with one or more of the strap-bands, as and for the purpose set forth.

95 In testimony whereof I affix my signature in presence of two witnesses.

DAVID G. GAY.
